CLAIM

The ornamental design for a sprayer with handle, as shown and described.

DESCRIPTION

FIG. 1 is a perspective view of the sprayer with handle showing our new design,
FIG. 2 is another perspective view thereof;
FIG. 3 is a front view thereof, the rear view being a mirror image of the front view;
FIG. 4 is a top plan view thereof;
FIG. 5 is a bottom view thereof;

(Continued)

FIG. 6 is a right side view thereof; and,
FIG. 7 is a left side view thereof.

The broken lines depict portions of the sprayer with handle
that form no part of the claimed design.

1 Claim, 7 Drawing Sheets
